JOHN V. DENISON, OF STEVENSON, ALABAMA.

LUMBER PACKAGE.

Application filed October 25, 1924. Serial No. 745,863.

My invention relates generally to the art of making bundles and bales and particularly to making packages of lumber, which lumber is of size and quality requiring careful handling and protection against soiling and bruising and breaking and moisture and theft during transportation and while being kept in stock.

One of the uses to which I have put my improvement in regular practice is the packaging of cedar lumber made for lining moth-proof closets and boxes and for similar purposes, this cedar lumber being cut to the uniform width of two and one-half inches and to the uniform thickness of three-eighths of an inch, while the pieces are of varying lengths. This variation in length is due to the variation in the length of logs or blocks of cedar from which the boards or strips are cut. Cedar trees do not grow large and they are so scarce as to require sawing trunks or blocks of any length which will produce these thin boards of a length which can be used. And it is to be noted that cedar wood is soft and for that reason requires proper packaging; and proper packaging includes giving to the package sufficient strength to prevent breaking of the pieces.

For convenient marketing of this lumber, it is desirable to make standard or unit packages, packages which contain definite or uniform quantities of surface measurement of the lumber. This reason is similar to the reason for making packages of cloth containing definite or uniform numbers of yards of the cloth.

In practice I have found that eight feet is a suitable length for these packages, and I have made this a standard length. This is convenient for handling and for transportation, and conforms approximately to the maximum length of pieces sawed for this trade in connection with my work.

It is also desirable that every package be of uniform thickness or cross section from one end of the package to the other, and that the package be thick enough to make it sufficiently strong to avoid breaking any of the pieces in the package during handling or transportation. The package should also include a protective covering sufficient to prevent soiling and particularly to prevent

bruising of the pieces and to keep the lumber free from moisture.

These various conditions or requirements are met as will appear further on.

In the accompanying drawings,

Fig. 1 is a perspective of a cedar lumber package made according to my invention, a part being broken away;

Fig. 2 is an elevation showing a surface made up of edges of the lumber, the cover having not yet been applied;

Fig. 3 is a plan of the package shown by Fig. 2;

Fig. 4 is an elevation, in full size, of a part of the structure as shown in Fig. 2;

Fig. 5 is a cross section, in full size, on the line, 5-5, of Fig. 2, looking toward the right;

Figs. 6 and 7 are detail views showing a shipping tag applied to the package;

Fig. 8 illustrates a sealing patch.

Referring to the drawings, A. A are the boards or strips of lumber. Each piece, A, has along one side edge a groove, A¹, and along its other side edge a tongue, A², and across one end a groove, A³, and across the other end a tongue, A⁴.

As shown best in Fig. 5, the boards are placed in horizontal layers, two pieces being placed side by side, the edge of one piece bearing the tongue and the edge of the other piece bearing the groove being brought together and the tongue entering the groove. One or more of the lower layers and of the upper layers are preferably formed of pieces which are of the full length of the package. The intermediate layers are made of pieces of full length or of any length which will produce the full length of the package, pieces being selected which will, when laid in position end to end, make the full length or eight feet. Thus two pieces or several pieces may be placed end to end to make the full length. This is the preferred way. But spaces may be left between the ends of the short pieces. That will require more layers to give the package the chosen number of lineal feet of boards.

It has already been stated that the tongues and grooves on the meeting side edges of the pieces are to be interlocked or interengaged. The pieces which are shorter than

full length are preferably to be so placed as to bring tongues and grooves on the meeting ends, and those tongues and grooves are to be interlocked or interengaged. This 5 interlocking of the tongues and grooves along the meeting side edges and along the meeting end edges of the pieces serves to reduce the dimensions of the package according to the depth of the grooves, and this 10 arrangement tends to avoid the bruising of the tongues and the lips at the sides of the grooves. Furthermore, this interengagement of the tongues and grooves on the meeting side edges and end edges of the pieces 15 tends to give the finished package such strength and stability as could not be had otherwise. The condition thus produced approaches the condition which would exist if the package consisted of unitary boards of 20 the full length and full width of the package. Making the package of uniform cross-section also contributes to strength.

The number of layers is made sufficient to put into the package the chosen or standard 25 number of feet of surface measurement.

When the body of the package has been arranged as above described, any desired 30 number of bands, B, are placed transversely around said body. Said bands are preferably formed of metal. The drawings show 35 the body of the bands composed of wire, the ends of which are held by sheet metal buckles, B¹, of any well-known form.

The body is now ready to be enclosed in 40 the cover, C. This is preferably formed of paper which is strong and adapted to prevent the passing of moisture. A sheet of such paper is folded around the body and has its side edges overlapping at C¹. The 45 end edges are folded over each other as shown at C². Then a sealing strip, C³, of paper is applied lengthwise along and over the joint formed at C¹ and over the ends of the package. Thus all the edges of the 50 cover are well held and the cover neatly and effectively sealed, the cover being adapted to prevent soiling and to exclude moisture and to prevent bruising of the strips of lumber and to add strength to the package and to prevent unauthorized removal of parts of the lumber pieces.

A further step consists in applying one or more shipping tags in a secure manner. This is done by securing such tag or tags 55 to one or more of the wire bands, B. These bands being covered by the package cover, C, it is necessary to puncture the paper at the place where the tag is to be attached. In Fig. 6, a hook, H, is driven through the 60 paper cover and under a band, B, and the latter when drawn outward far enough to allow the wire cord, T¹, of the tag, T, to be passed through the opening in the paper and across the wire, B, between the latter 65 and the adjacent lumber. Then the hook

is to be removed and the cord, T¹, twisted upon itself for effective holding. In Fig. 7, an open wire link, T², extends through the eye of the tag, T, and through an opening in the paper cover and across one of the 70 bands, B, between the latter and the lumber. This link is applied by passing the long arm of the link, T², through the paper cover and across the band, B.

When the tag has been applied, the small 75 opening thus formed in the cover may be closed by means of a patch of paper, D, or other sheet-form material having a slot, D¹, this patch being secured to the cover by adhesive after being put into position by 80 moving the patch to pass the cord, T¹, or the link, T², through the slot, D¹, to the middle of the patch.

While the drawings show the package 85 having two boards or strips laid side by side to form the layers in the package, it is to be understood that these layers may be formed of any other number of boards, it being remembered that the package is to 90 contain a chosen or standard number of board feet.

Heretofore it has been the practice with manufacturers of such cedar lumber to assort and bundle or package the pieces or 95 boards according to length, pieces 1 foot long forming a package and other pieces in the same manner forming bundles or packages of their lengths until the longest pieces are bundled by themselves. Thus none of 100 the bundles are made composite. Every bundle contains pieces of its length. In the handling of this lumber, it must be sought to avoid bruising the ends of the pieces which are at the ends of the packages. If 105 the lumber is assorted and bundled according to lengths, the number of exposed ends of pieces is increased. In my composite package, the number of exposed ends is limited by placing the shorter pieces between the full length pieces. If two short 110 pieces are thus placed end to end between full lengths, those two short pieces have four ends but only two of their ends are placed at the ends of the bundle. If four 115 short pieces are thus placed end to end between the full length pieces, those four pieces have eight ends, but only two of those eight ends are placed at the ends of the package. If eight short pieces are thus 120 placed end to end between the full length pieces, those eight pieces have sixteen ends, but only two of those sixteen ends are placed at the ends of the package. In this connection, it is to be observed that this cedar lumber is soft and easily bruised. It is also to be remembered that the production 125 of this lumber is costly and that its selling price is high.

By way of summary, it may be stated 130 that in my composite package there are full

length pieces or boards and shorter pieces or boards so placed as to be held and protected by the full length pieces or boards.

And by forming this composite package in this manner all the packages are alike and have equal content. That facilitates computation of the content of several or a car load of packages. It is only necessary to multiply the content of one package by the number of packages. That is a decided convenience for dealers and users. Furthermore, the number of packages is limited, because there are no short packages.

I claim as my invention,

15 1. A lumber package comprising wooden boards and bands and a cover, the boards being tongued and grooved and being of uniform width and laid side by side and flatwise upon each other and their meeting edges making tongue-and-groove engagement and the outer boards being of a standard length and the full length of the package and intermediate boards being shorter and laid end to end and having aggregate 20 length approximately equal to the length of the full length boards, the bands surrounding the group of boards, and the cover surrounding the group of boards and the bands, substantially as described.

30 2. A lumber package comprising wooden boards and bands and a cover, the boards being of uniform width and tongued and grooved at their side edges and at their ends and being laid side by side and flatwise upon each other and their side edges making tongue-and-groove engagement and the outer boards being the full length of the package and intermediate boards being shorter and laid end to end and having aggregate 35 length approximately equal to the length of the full length boards and their meeting ends making tongue-and-groove engagement, the bands surrounding the group of boards, and the cover surrounding the group of boards and the bands, substantially as described.

40 3. A lumber package comprising flat boards, binding members, a wrapper secured around the group of boards and the binding members, and a tag, the body of the wrapper having a perforation adjacent one of the binding members and the tag having an attaching member extending through said perforation and around said binding member, substantially as described.

45 4. A lumber package comprising flat boards, binding members, a wrapper secured around the group of boards and the binding members, a tag, the body of the wrapper having a perforation adjacent one of the binding members and the tag having an attaching member extending through said

perforation and around said binding member, and a cover patch over said perforation, substantially as described.

5. A lumber package comprising wooden boards and bands, the boards being tongued and grooved and being of uniform width and laid side by side and flatwise upon each other and their meeting edges making tongue-and-groove engagement and the outer boards being the full length of the package and intermediate boards being shorter and laid end to end and having aggregate length approximately equal to the length of the full length boards, and the bands surrounding the group of boards, substantially as described.

6. A lumber package comprising wooden boards and bands, the boards being tongued and grooved at their side edges and at their ends and being of uniform width and laid side by side and flatwise upon each other and their side edges making tongue-and-groove engagement and the outer boards being the full length of the package and intermediate boards being shorter and laid end to end and making tongue-and-groove engagement at their meeting ends and having aggregate length approximately equal to the length of the full length boards, and the bands surrounding the group of boards, substantially as described.

7. A lumber package comprising wooden boards and bands, the boards being tongued and grooved and being of uniform width and laid side by side and flatwise upon each other and their meeting edges making tongue-and-groove engagement and certain of the boards being the full length of the package and certain of the boards being shorter and laid end to end and having aggregate length approximately equal to the length of the full length boards and the bands surrounding the group of boards, substantially as described.

8. The herein described method of making a lumber package, which method consists in laying flat boards upon each other to form the body of the package, then placing bands around said body, then securing a wrapper around said body and the bands, and then attaching a tag to one of the bands by making a perforation at one of the bands and forcing the adjacent part of the band outward and passing the attaching member of the tag through said perforation and around said band, substantially as described.

In testimony whereof I have signed my name, this twentieth day of October, in the year one thousand nine hundred and twenty-four.

JOHN V. DENISON.
